UNITED STATES PATENT OFFICE.

JAMES M. McCLELLON, OF EVERETT, MASSACHUSETTS.

FIRE-BOX CONSTRUCTION.

1,078,933.

Specification of Letters Patent. Patented Nov. 18, 1913.

Application filed December 26, 1911. Serial No. 667,841.

To all whom it may concern:

Be it known that I, JAMES M. McCLELLON, a citizen of the United States, and a resident of Everett, county of Middlesex, and State 5 of Massachusetts, (whose post-office address is 159 Beacham street, Everett, Massachusetts,) have invented an Improvement in Fire-Box Construction, of which the following description, in connection with the accompanying drawings, is a specification, like 10 characters on the drawings representing like parts.

This invention relates to locomotive and other fire-boxes and among other objects 15 provides an improved crown for the fire-box and means for promoting circulation in the side walls of the fire-box whereby steam is generated more quickly and economically than heretofore.

20 The character of the invention may be best understood by reference to the following description of an illustrative embodiment thereof shown in the accompanying drawing, wherein:

25 Figure 1 is a rear end elevation of a fire-box embodying the invention; Fig. 2 is a vertical section taken on line 2—2 of Fig. 1, parts being broken away; Fig. 3 is a transverse vertical section through the fire-box; 30 and Fig. 4 is a side elevation of Fig. 3 having parts broken away to disclose the internal construction of the side walls.

Referring to the drawing, the illustrative 35 fire-box construction shown therein as embodying the invention comprises side walls 1 consisting of a series of upright hollow sections preferably of the character set forth in United States Letters Patent, No. 963,627 granted to me July 5, 1910. These sections

40 may be secured against expansion in the direction of the length of the series by stay sleeves 3 and tie rods 5 similar to those set forth in my copending application, Ser. No. 667,841 filed Dec. 26, 1911. The lower ends 45 of the sections may be contracted or reduced and formed to straddle a foundation ring 7 and be secured thereto by suitable through bolts 9. To provide tight closure of said

sections directly above said ring each section is provided with a cup 11 welded or 50 otherwise secured to such section.

The end sections of the series constituting the sides of the fire-box may be riveted or otherwise secured to a flue sheet 13 receiving usual flues 15 contained in a barrel 17. 55 To provide an expansible connection between said flue sheet and barrel the former is provided with a flange 19 extending around its sides and top secured by a butt strap 21 to a throat sheet 23 secured to the barrel of 60 the fire-box, said throat sheet and flue sheet being spaced at their bases and secured by through rivets to a mud-ring section 24 superposed on and secured to the foundation ring 7 referred to by threaded studs 24^a projecting down through said foundation ring to receive nuts 24^b. To conduct water from 65 the barrel to the sections and thence from one section to another the flue sheet and adjacent walls of the sections are provided with registering apertures in which are expanded or otherwise secured suitable nipples 27. The upper ends of the sections may 70 be closed by cups 29 riveted, welded or otherwise secured to said sections.

To facilitate the cleaning or flushing out 75 of the sections the upper cups may be provided with closure means herein shown as plugs 31 threaded into apertures in said cups and the lower ends of the sections may 80 be provided with similar means 33 entering said sections immediately above the cups closing said ends.

An important feature of the invention relates to the provision of means for promoting 85 circulation in the wall sections. The hottest side of a section faces the interior of the fire-box and is the most active steam generating portion of the section. There is, therefore, a greater ebullition or steam 90 developing process taking place along said side than along the opposite or outer side of the section. The rising of bubbles occasioned by this ebullition process creates a rising current or circulation of water along 95 the fire side of the section, whereas cooler

water will be adjacent the opposite or outer side of the section, and unless separated from the hotter water is more or less of a drag or retard to the rising current referred to.

An important feature of the invention relates to the provision of means for separating the rising stream of steam bubbles generated along the fire side of the fire-box 10 from the less active water at the opposite side of the fire-box so that the objectionable retard referred to is eliminated and the generation and upward circulation of steam bubbles is greatly promoted. To this end 15 each section may be provided with partition means shown herein in the form of a thin plate 35 located between the fire and outer sides of the section and extending longitudinally thereof, thereby dividing the section 20 into two passages or chambers. Preferably said plate extends nearly the entire length of the section and terminates short distances from the closing cups at the opposite ends of the section. This plate may be 25 secured in position in any suitable manner. As shown herein, the ends of the plate are bent or wrapped around the upper and lower stay sleeves 3 referred to of the section and riveted or welded to the body of 30 the plate as at 37. To further secure said plate in place, straps 39 are provided embracing the sleeves intermediate the ends of the plate and are riveted to the latter. By thus dividing a section a smaller volume of 35 water is presented at a time to the hot steam generating fire side of the section than in a section of the same size without such division. As a result a large stream of steam bubbles is created which in their effort to 40 rise to the surface of the water, create an upward circulation of water in the steam generating passage of the section and a rapid generation of steam is effected.

On reaching the upper end of the section 45 the steam bubbles and some of the hot water pass into a crown to be described, and liberate steam while the bulk of the rising current of water which carried the bubbles, passes around the upper end of the partition 50 down through the outer passage, thence around the lower end of the partition and up again through the steam generating passage. Thus a continuous circulation is effected around the partition, greatly increasing 55 the steam generating capacity of the section, with resultant economy and improved operation. The sections collectively constitute a hollow wall having spaced fire and outer sides with a partition between 60 them creating a circulation up along the fire side and down the opposite side of the wall as a whole. At the same time there is an individual circulation in each section independent of the circulation in another sec-

tion. As a result the steam generating activity in the hotter sections adjacent the flue sheet is not retarded by less activity in cooler sections of the wall near the fire door end of the fire-box. The rapid circulation and rapid supply of water to and 65 along the fire sides of the sections prevents over-heating of said sides and tends to maintain a uniform temperature throughout, thereby eliminating unequal temperatures such as would be liable to cause unequal expansion and set up stresses and strains tending to weaken or distort the sections or wall as a whole.

An important feature of the invention relates to the crown of the fire-box. As shown 80 herein, this crown comprises a plurality of drums including side drums 41, and an intermediate drum 47 preferably so placed that its bottom is somewhat beneath those of the side drums. The side wall sections 85 project up and overlap the sides of said outer drums and are riveted or otherwise secured thereto. To permit the bubbles and steam generated in the sections to rise into said drums and to the surface of the water 90 therein, said sections and drums may be apertured to receive nipples 44 expanded or otherwise formed into said apertures.

To retain as much as possible the cylindrical form of the drums, cover portions of 95 the under surfaces of the side drums, contribute to the support thereof beneath the same and permit communication with said drums near their bottoms, the portions of the side wall sections overlapping said drums 100 are curved to conform to the contours of said drums. The wall sections as shown herein have sides convexed or bulged toward the interior of the fire-box, and in order that the sections may be secured to said 105 drums without leaving spaces between the sections, their bulged portions are flattened so that the sections are not only curved but flattened to conform to the crown drums.

Where a crown is composed of drums 110 placed in the same horizontal plane with contacting sides secured centrally together, as soon as the water level falls below a horizontal plane passing through the centers of the drums, portions of the latter below their 115 meeting points commence to be uncovered and by the time the water reaches nearly to the bottoms of the drums there will be large extensive under surfaces of the drums uncovered by the water. The fire playing on such uncovered portions of the drums is very apt to burn, weaken and injure the same.

An important object of the invention is to provide a crown having the strength giving characteristics of a cylinder and at the same time provide an under fire exposed surface which will be entirely covered by 125

water until the water level is lowered nearly to the bottoms of the drums. To this end the intermediate drum 43 referred to is formed to occupy the space between the side drums 41 in such a manner that it will substantially cover portions of the side drums extending from a plane passed through their centers to points nearly to the bottoms of said side drums. As a result, the bottoms or 10 fire exposed portions of the drums will approach a flat plane and the water level can fall nearly to the bottoms of the drums before uncovering any fire exposed portions thereof. Preferably the bottoms of the 15 drums are not flat but their curved form is retained to present central pockets into which the water will gravitate as it approaches the drum bottoms or the points last uncovered by the water.

20 It will be observed that the vertical distance from the lowest points of contact of the drums from the lowest points of the drums is slight. The water may safely drop somewhat below said points of contact since 25 the volume of water at the bottoms of the drums adjacent said points will be effective to conduct heat from the small surfaces thus exposed and prevent their burning out, but when the water has dropped a little farther 30 the total volume in the drums will be so slight that it will flash into steam. Thus the water level may be safely lowered almost to the extreme lowest points of the drums before being dangerously exhausted therefrom. The water will flow into the crown 35 drums not only through the nipples connecting the side walls thereto, but also through the open ends of the drums entering the barrel and also, as more fully hereinafter described, through the nipples connecting the 40 top of the fire door wall to the under surfaces of the drums. As a result, water will continue to be supplied to the drums after the water level has lowered beneath the nipple 45 entrances from the side walls to the drums. To permit water to circulate from the side drums to the intermediate drum, nipples 43 may be expanded in registering apertures in said drums.

50 An important feature contributing to the prevention of the dropping of the water beneath fire exposed portions of the drums and facilitating the nipping and riveting of the same together, consists in flattening the 55 sides of the drums so that they have a considerable extent of contact surface. The front ends of the side drums extend through apertures in the flue sheet and are riveted or otherwise secured to collar flanges 45 bent 60 from said sheet away from the interior of the fire-box. To permit circulation of water to and from the barrel and the intermediate drum, the latter is formed with a collar 47 preferably integral therewith and project-

ing therefrom flush with the bottom thereof 65 through a flange 49 surrounding an aperture in the flue sheet and projecting away from the fire-box interior, said collar being riveted or otherwise secured to said flange.

In order that the flue sheet drum receiving 70 apertures may not be sufficiently close to one another to weaken the flue sheet, in some instances it may be desirable to reduce the width of the end portion of the intermediate drum where it joins the flue sheet. As 75 shown herein, the collar of the intermediate drum is considerably smaller than the diameter of the drum, and the sides of the drum adjacent the flue sheet converge toward said collar as at 51, thereby not only 80 permitting ample material in the flue sheet between the drum receiving apertures, but also providing a gradual conducting surface from the drum to its collar, preventing the formation of any abrupt shoulders such as 85 might invite sediment or secretion. As stated, the intermediate drum collar is preferably considerably smaller than the diameter of the drum. To fill the space above this 90 collar, the drum is provided with a head 53 formed to fit the contour of said collar and having a flange extending away from the flue sheet into the drum and following the contour of the upper portion of the head, and a flange oppositely bent into the upper 95 portion of said collar and following the contour thereof, said flanges being riveted or otherwise secured to the drum and collar respectively. To contribute to the securing of the intermediate drum in place the head at 100 the collar end of the drum may be riveted or otherwise secured to the flue sheet.

The rear or fire door end of the wall may comprise spaced outer and inner sheets 55 and 57, the inner having a long flange 59 overlapping and riveted to a short flange 61 of the outer along the sides and top of said wall. These end sheets may be formed to fit the end of the fire box as determined by the side walls described, and the inner sheet 105 110 may be riveted to the rear sections of said side walls. To secure said rear wall to said rear sections the tie rods 5 may be extended beyond said sections through the spaced sheets constituting said rear wall and may have sleeves 3^a thereon interposed between said sheets to assist in holding the same in position. To provide communication from said side walls to said rear wall the inner sheet may be apertured and nipped to said 115 120 sections adjacent the bottom of the flue sheet. The lower ends of the spaced sheets forming the rear wall are secured by through rivets to a mud ring section 62 superposed on the foundation ring 7 referred to and secured 125 thereto by threaded studs projecting down through said foundation ring to receive suitable nuts. The intermediate drum has a

bumped flanged head 63 riveted to its end adjacent the rear wall of the fire-box. The upper end of the rear wall is formed to follow the contours of the under sides of the 5 crown drums and may be riveted and nipped thereto. To receive steam from the intermediate drum there may be provided directly above the same a steam drum 67 nipped and riveted to said intermediate drum 10 and having a bumped head 67^a adjacent the rear end of the fire-box and a flanged head 67^b at the flue sheet end of the fire-box riveted to said intermediate drum and sheet and provided with an aperture registering 15 with a similar aperture in the flue sheet, said apertures receiving a suitable nipple 69 expanded therein to conduct the steam from said steam drum to the barrel.

In use, the water is fed from the barrel 20 to the lower ends of the side wall sections and into the space between the sheets comprising the fire door wall. As the water rises in the sections and the barrel it will flow into the crown drums and normally 25 will be maintained a substantial distance above the bottoms of the drums. The hot fire in the fire-box will heat the section walls facing the interior of the fire-box, creating a rapid circulation in each of the sections and 30 developing steam which passes from the sections into the side drums and is liberated on reaching the surface of the water therein. The hot fire playing on the under surfaces 35 of the crown drums will also assist in developing steam, which will be free to pass from the crown drums through their open ends into the barrel and also will be free to pass from the intermediate drum into the steam drum above it and thence into said barrel.

40 Owing to the shape and arrangement of the crown drums the water level may be permitted to drop in said drums and barrel until nearly on a level with the lowest points of the crown drums before uncovering water 45 from surfaces of said drums exposed to the fire. As a result a considerable range of water level in the barrel and crown may be had, and the liability of burning, weakening or injuring the crown from exhaustion of water 50 therefrom is reduced to a minimum. The crown described not only has the advantages referred to with respect to its capacity for safe low water level, but also the form and arrangement of the drums present a crown 55 of great strength and rigidity. This is due, among other things, to the fact that the drums are of general cylindrical shape and the pressure of the steam therein tends to maintain this cylindrical shape since it is a 60 well known fact that pressure in a container tends to cause the same to assume a form circular in section. Preferably, adjacent drums are each flattened at their surfaces of contact and thus any pressure in one tending

65 to destroy this flattening is counteracted by the pressure in the other, and the tendency of such pressure is to maintain the drums in close intimate contact. The flattened surfaces of the drums present substantial areas 70 for receiving the nipples providing communication between the drums and for receiving the rivets for securely holding the drums together. The crown as a whole is securely supported and positioned by its ends entered 75 through the flue sheet and its opposite ends resting on the front wall of the fire-box. The crown as a whole is further supported by the side wall sections, the flattened and curved portions of which in a sense constitute seats for receiving and supporting the 80 sides of the drums throughout the lengths of the sides of the fire-box.

The fire-box as a whole is inherently extremely strong in construction without the necessity of using stays and well able to 85 withstand the rack and severe use which locomotive fire-boxes must necessarily undergo.

It is not indispensable that all of the features of the invention be used conjointly since some of them may be used separately 90 to advantage. In some instances it may be desired to use instead of a fire door wall composed of spaced sheets a fire door wall composed of upright sections having the general characteristics of the wall shown in said 95 Letters Patent No. 963,627 referred to.

Having described one embodiment of my invention without limiting the same thereto, what I claim as new and desire to secure by Letters Patent is:

1. In a fire-box, the combination of a crown comprising a plurality of complete drums having adjacent sides flattened and assembled to maintain their fire-exposed surfaces covered with water until lowered nearly to the bottoms of said surfaces, and means providing communication between 105 said drums through said flattened sides.

2. In a fire-box, the combination of a crown comprising a plurality of drums formed and assembled for contact with one another beneath the center of one of said drums to reduce the under fire exposed surface thereof.

3. In a fire-box, the combination of a 115 crown comprising a plurality of drums having flattened adjoining sides extending beneath the center of one of said drums to reduce the fire exposed surface thereof and delay the uncovering of said surface until 120 the water is nearly exhausted therefrom.

4. In a fire-box, the combination of a crown comprising a plurality of drums including side drums and an intermediate drum located a substantial distance beneath 125 the centers of said side drums to reduce the fire exposed surfaces of said drums.

5. In a fire-box, the combination of a

- crown comprising a plurality of drums including side drums and a smaller intermediate drum contacting with sides of said drums beneath their centers.
5. In a fire-box, the combination of a crown comprising a plurality of drums including side drums and an intermediate drum, said drums having contacting flattened side portions extending beneath the 10 centers of said side drums.
7. In a fire-box, the combination of a crown comprising a plurality of drums including side drums and an intermediate drum nippled and riveted thereto beneath a 15 plane passing through the centers of said side drums.
8. In a fire-box, the combination of a crown comprising a plurality of drums including side drums and an intermediate 20 drum having a collar of less diameter than said drum entered through an aperture in a flue sheet and secured to said sheet.
9. In a fire-box, the combination of a flue sheet, a crown including side drums and an 25 intermediate drum having a collar of less diameter than said drum entered through a flanged aperture in said flue sheet and secured thereto, said drum having flattened portions inclining from a wall of the drum 30 toward said collar.
10. In a fire-box, the combination of a flue sheet and a crown comprising side drums and an intermediate drum having a collar entered through a flanged aperture of said 35 flue sheet and a head in said drum adjacent said collar.
11. In a fire-box, the combination of a flue sheet and a crown comprising side drums and an intermediate drum having a 40 collar integral therewith projecting from a flanged aperture in said flue sheet.
12. In a fire-box, the combination of a flue sheet and a crown comprising side drums and an intermediate drum having a 45 collar flush with the bottom of said drum and projecting through a flanged aperture in said flue sheet.
13. In a fire-box, the combination of a flue sheet and a crown comprising side drums 50 and an intermediate drum having a collar at one end smaller than the drum diameter and projecting through a flanged aperture in the flue sheet and a head in the collar end of said drum filling the space around 55 said collar and having a flange projecting into and secured to the drum and a flange projecting away from the interior of the fire-box and secured to said collar.
14. In a fire-box, the combination of a 60 crown comprising side drums and an intermediate drum contacting with said side drums throughout a substantial part of their under sides, an end wall and a flue sheet and means permitting communication of said intermediate drum with said end 65 wall and through said flue sheet with the barrel of the fire-box.
15. In a fire-box, the combination of a crown comprising side drums and an intermediate drum adjacent thereto beneath a 70 plane passing through the centers of said side drums and a steam drum located above said intermediate drum.
16. In a fire-box, the combination of a crown comprising side drums and an intermediate drum communicating therewith and a steam drum above said intermediate drum 75 nippled and secured thereto.
17. In a fire-box, the combination of side walls comprising a series of upright hollow 80 sections communicating with one another adjacent their lower ends, a barrel and flue sheet having provision for conducting water to said side walls, a crown comprising a plurality of drums, the latter being apertured 85 and nippled to the upper end portions of said side wall sections, and an end wall communicating with said drums, thereby providing a construction permitting a circulation from the barrel up through said side 90 and end walls through said drums and back to said barrel.
18. In a fire-box, the combination of a crown comprising a drum having a flattened portion and another drum having a flattened 95 portion contacting with the flattened portion of the other, and means to secure said portions together.
19. In a fire-box, the combination of a crown comprising drums, each having portions flattened beneath the center of one of 100 said drums, and means to secure said flattened portions together.
20. In a fire-box, the combination of a crown comprising a plurality of drums, each 105 having flattened sides, and nipples in said sides providing communication from one of said drums to another.
21. In a fire-box, the combination of a crown comprising a plurality of drums, each 110 having flattened sides apertured to provide communication from one to another through said flattened sides.
22. In a fire-box, the combination of crown drums and side wall sections curved 115 to conform to the contours of said drums.
23. In a fire-box, the combination of crown drums and side wall sections bulged toward the interior of the fire-box and having portions curved and flattened to conform 120 to the contours of said drums.
24. In a fire-box, the combination of crown drums, side wall sections having portions curved to conform to the contours of said drums and means to secure said portions to said drums.
25. In a fire-box, the combination of crown drums, side wall sections having por-

- tions overlapping and curved to conform to the contours of said drums, said portions having provision providing communication with said drums and means to secure said portions to said drums.
26. In a fire-box, the combination of crown drums and side wall sections having portions curved to conform to the contours of said drums and nippled and secured thereto.
- 10 27. In a fire-box, the combination of
- crown drums and side wall sections having portions formed to present curved seats for receiving and contributing to the support of the sides of the drums. 15
- In testimony whereof, I have signed my name to this specification, in the presence of two subscribing witnesses.
